UNITED STATES PATENT OFFICE.

AUGUST SUNDH, OF YONKERS, NEW YORK.

SYSTEM OF TRAIN CONTROL.

No. 823,196.

Specification of Letters Patent.

Patented June 12, 1906.

Application filed March 16, 1905. Renewed December 4, 1905. Serial No. 290,175.

To all whom it may concern:

Be it known that I, AUGUST SUNDH, a citizen of the United States, residing at Yonkers, in the county of Westchester and State of New York, have invented certain new and useful Improvements in Systems of Train Control, of which the following is a specification.

My invention relates to an improved system of control for electric trains; and its object is to provide a simple and efficient system which will overcome some of the difficulties in the systems now in use.

I will describe my invention in the following specification and point out the novel features thereof in claims.

Like characters of reference designate corresponding parts in all of the drawings, of which—

Figure 1 is a side elevation of parts of two railway-cars with certain parts broken away and with my invention applied thereto. Fig. 2 is a side elevation showing a train comprising two motor-cars and an idle car or "trailer" between them with my invention applied to the train. Fig. 3 is a side elevation of a master-switch. Fig. 4 is a similar view of the same switch with its handles taken off and its cover removed. Fig. 5 is a plan view of a detail of one of the master-switches. Fig. 6 is a sectional view of a master-switch, the section being taken through the line A B of Fig. 3. Fig. 7 is an end view of my electromagnetic actuating device or "actuator" connected to an ordinary electric car-controller. Fig. 8 is a side elevation, partly in section, of a part of this actuator, showing a series of actuating magnets or solenoids; and Fig. 9 is a plan view of the controller and its connected actuator. Fig. 10 is a vertical section of a special two-part relay, and Fig. 11 is a horizontal section of the same device. Fig. 12 shows diagrammatically a preferred system of wiring for two motor-cars. Fig. 13 is a detail of a part of the actuator.

Like characters of reference designate corresponding parts in all of the figures.

10 designates a railway-car, 11 its wheels, 50 and 12 the track over which it is adapted to run.

13 is a third rail or power-rail on which collector-shoes 14 run.

20 20 designate electric motors, which are

connected by suitable gearing 16 to drive the 55 wheels 11.

50 designates a master-switch, which comprises a reversing-switch 51, which may be manually operated by means of a hand-lever 52, and a controlling-switch 53, which may 60 be manually operated by means of a hand-lever 54. The hand-lever 52 of the reversing-switch is rigidly attached to a shaft 52^A, which carries on it a locking-cam 52^B and a switch-arm 52^C. The switch-arm carries on it two 65 insulated brushes 1 and 2, which are connected together by an electrical conductor 3 and are adapted to span and to electrically connect a stationary contact 51^A with either the stationary contact 51^B, which they do 70 when the parts are in the position shown in Fig. 4, or with the stationary contact 51^C, which they will do when the switch-arm is moved over to the right.

The hand-lever 54 of the controlling- 75 switch is rigidly attached to a shaft 54^A, which extends to the back of the master-switch and which carries at its rear end a plate 54^B, which is rigidly attached to the shaft 54^A. One end of a spiral spring 55 is 80 attached to this plate at 55^A, and the other end of this spring is attached at 55^B to a sleeve or collar 56, which is mounted upon and attached to another sleeve 57, so that the two move together. The sleeve 57 carries on it a switch-arm 57^A and a cam 57^B. These may be made integral parts of the sleeve 57, as shown in Fig. 6, if desired. The switch-arm carries insulated brushes 4 and 5, which are electrically connected by means of 85 a conductor 6. The brush 4 is adapted to bear upon and make electrical connection with a circular contact-piece 53^A and through the conductor 6 and the other brush 5 to make electrical connection between this 90 circular conductor and any desired one of a series of stationary contacts 53^B, 53^C, 53^D, 53^E, 53^F, or 53^G, according to the position of the switch-arm 57^A. The various stationary contacts of the reversing-switch and of the 95 controlling-switch may be mounted upon a base 58 of slate or other suitable insulating material.

The inner edge of the collar 56 is made into the form of gear-teeth 56^A, so that it forms a 105 gear or pinion, which meshes with a rack 56^B, to one end of which a piston 56^C is attached. This piston works in a cylinder 56^D, which is

arranged to act as a dash-pot and to prevent the collar 56, sleeve 57, and switch-arm 57^A from moving rapidly in one direction; but a valve 56^E is provided in one end of the cylinder 56^D, which is arranged to destroy its retarding effect in the other direction.

The hub of the handle 54 is provided with a projecting lug 54^C, which is adapted to engage with a similar lug 57^C on the other end 10 of the sleeve 57 and is arranged to move the sleeve positively in one direction, but not in the other. When the hand-lever 54 is moved to the left, the lug 54^C will thereby be moved away from the lug 57^C. At the same time 15 the plate 54^B will be turned and the spring 55 tightened thereby. The spring will then have a tendency to move the collar 56 and its connected parts to the left, and this movement will take place governed by the action 20 of the dash-pot 56^D. The switch-arm 57^A will then move its brushes over the stationary contacts slowly under the influence of the dash-pot. This movement will continue until the lug 57^C meets the lug 54^C. If the 25 hand-lever has been moved over to its extreme position, this will not occur until the switch-arm has completed its movement and has moved its brush 5 around onto the stationary contact 53^G; but the hand-lever may 30 be stopped at intermediate positions, in which case the lugs 57^C and 54^C will meet when the brush 5 is on one of the other stationary contacts. Spring-locks 54^D may be provided on 35 the hand-lever 54, which are adapted to engage with indentations in the case 58 of the master-switch, and to thereby hold the hand-lever in desired position. It will be seen then that the switch-arm 57^A may be arranged to move at any desired speed without 40 regard to the speed at which the operator moves the hand-lever.

Now when it is desired to move the switch-arm back to its central position the operator may move the hand-lever 54 back to the left. 45 The lug 54^C will then come into positive engagement with the lug 57^C and the hand-lever and the sleeve 57 will then move back together. As the retarding effect of the dash-pot 56^D is destroyed by the valve 56^E, this 50 movement may be made as rapidly as desired.

It will be noticed that the cam 57^B, which I have shown is arranged to move in unison with the switch-arm 57^A, has a depression at 55 its upper portion. One end of a sliding bolt 59 is pressed into this depression by a spring 59^A. When the cam is rotated, however, its surface pushes the sliding bolt upward against the action of the spring 59^A. A recess 52^B, which is in 60 the path of the movement of the sliding bolt 59 when the switch-arm 52^C of the reversing-switch is in the position shown. This locks the reversing-switch, so that it cannot be 65 moved until the switch-arm 57^A of the con-

trolling-switch has been brought back to its central or stop position. When it is thus brought back to center, the depression or recess in the cam 57^B will again be opposite the end of the sliding bolt 59, and the spring 59^A 70 will move the bolt back out of locking position. Another recess 52^E is provided in the locking-cam 52^B and is arranged to lock the reversing-switch in a similar manner when the switch-arm 52^C has been moved over to the 75 right. Thus it will be seen that the reversing-switch cannot be operated except when the controlling-switch is in its central or neutral position.

In the drawings, 30 designates a special relay, which comprises two parts 31 and 32, which may be supported on the cars 10 by means of chains 33. These relays 30 are shown somewhat in detail in Figs. 10 and 11. Each part comprises a series of electromagnets 34^A, 34^B, 34^C, 34^D, 34^E, 34^F, and 34^G, each of which has a core 36 and a winding 36' and also a series of magnetoresponsive devices 35^A, 35^B, 35^C, 35^D, 35^E, 35^F, and 35^G. I have lettered the electromagnets in one of the 80 parts 32 of the relay 30 and the magnetoresponsive devices in the other part 31, as these are the ones which coact, and as the two parts 31 and 32 are substantially alike this will lead to no misunderstanding. The magnetoresponsive devices each comprise an armature 37, mounted upon a rod 38, which is supported in a frame or bracket 39. This rod 38 is provided with a collar 38', between which and the bracket 39 a spring 37' is 85 placed, which normally keeps the armature 37 and its connected parts in the position shown in the drawings. A stationary contact 40 is attached to but insulated from the bracket 39. The rod 38 passes through the 90 supporting part of this stationary contact, but is insulated from it by an insulating bushing, as shown. On the end of the rod 38 which is opposite that which holds the armature 37 a movable contact 41 is attached. 95 This is insulated from the rod, as shown. Electrical conductors 40' and 41' are connected to the stationary contact 40 and the movable contact 41, respectively. Each part 31 and 32 of the relay 30, with its series 100 of electromagnets and its series of magnetoresponsive devices, is inclosed in a suitable housing 31' and 32', which is preferably water-tight. The two parts are so arranged 105 that they may be connected together with the series of electromagnets in each part opposite the series of magnetoresponsive devices in the other part. When thus connected, each electromagnet with its associated magnetoresponsive device forms an operative unit, which may be called an "electroresponsive device," the purpose and function of which will be pointed out later. I prefer 110 to connect the two parts 31 and 32 by springs, as shown at 42 42, or by other yield- 115

ing means, so that the two parts may be pulled apart when desired. Conduits 42^A 42^A, arranged to carry electrical conductors to the relay mechanism, may be screwed into 5 the housings, as shown at 42' 42', and by such an arrangement the apparatus may be made dust-proof and water-tight.

I will now describe my electromagnetic actuator, which is shown somewhat in detail in Figs. 7, 8, and 9. It is shown in these figures connected to an ordinary street-car motor-controller 45, which is not shown in detail in the drawings, nor is it necessary to describe it at length, as such controllers are well known 10 to the art. It contains various switches and contacts whereby the connections of the motors 20 may be so made and changed that the motors may be started, stopped, reversed, or their speed varied at will. Such controllers 15 are usually provided with two shafts 46 and 47. 46 in this case connects with the moving parts of a reversing-switch. To this shaft I attach a gear 46^A and a pointer 46^B. The pointer serves the purpose of indicating the 20 position of the parts within the controller. The gear 46^A is arranged to mesh with a rack 62, which is attached to the plungers or cores 60' 61' of two solenoid-magnets 60 and 61. These solenoid-magnets will move the rack 25 62 to one side or the other when one or the other of them is energized, and thereby attracts its core. When the rack 62 is thus moved, it will cause the gear 46^A, the shaft 46, and its connected parts to be rotated. 30 Thus the reversing-switch may be actuated by the solenoid-magnets 60 and 61. When the solenoid-magnet 61 is energized, as it may be by causing an electric current to pass through its coils, it will attract its core 61' 35 and the latter through its mechanical connections will move the reversing-switch into such position that the pointer 46^B will stand, as shown in Fig. 7, over that portion of the case of the controller which is marked "Ahead." 40 In a similar manner the solenoid-magnet 60 will move the reversing-switch around until its pointer 46^B will stand over the word "Back."

A gear-wheel 47^A is attached to the end of 45 the shaft 47, and a pointer 47^B is also attached to this shaft. A toothed segment 63^A is securely attached to an actuating-shaft 63 and is arranged to mesh with the gear 47^A. On the other end of the actuator-shaft 63 an arm 50 63^B is secured, and this arm carries a weight 63^C. This weight is provided for the purpose of keeping the various parts in their off or neutral position when they are not moved out of such position by some other means. 55 It also serves the purpose of returning the parts to their neutral position after they have been moved away by some other force when that other force is removed. An inspection of Fig. 7 will show this clearly. The weight 60 63^B there has a tendency to move the shaft

63 and the segment 63^A to the left or anti-clockwise. It therefore has a tendency to move the gear 47^A and the shaft 47 in the opposite direction, and therefore to hold the controller in its "off" position, as indicated by 70 the pointer 47^B. An adjustable stop 63^D may be provided to limit the downward movement of this weight, and so take the strain off of the other parts of the apparatus.

A frame 69 is provided which may be attached to the controller 45 and which is arranged to hold the various parts of the actuator. A series of electromagnets 64, 65, 66, 67, and 68 is supported in this frame. Each of these magnets comprises a winding, as 75 shown at 68^A, and a core, as shown at 68^B. The upper part of each of these cores is provided with a rack, as at 68^C, on one side. Anti-friction-rollers, such as 68^D, are provided behind the rack part of each core to guide the 80 latter and to insure the racks properly meshing with toothed segments 64^E, 65^E, 66^E, 67^E, and 68^E. These toothed segments are loosely mounted upon the shaft 63 and engage with collars 64^F, 65^F, 66^F, 67^F, and 68^F, respectively, which are rigidly attached to the shaft 85 63 and are so set upon the shaft that they hold their respective toothed segments, and consequently their respective magnet-cores, in different relative positions. This is clearly 90 shown in Fig. 8, where the magnet-core 64^B is raised but slightly above its lowest position, 65^B is raised farther, and so on, until 68^B, which is raised farther than all the others. It will be understood from the previous part 95 of the description of this apparatus that it is the weight 63^C which raises these cores and holds them in the positions shown in Fig. 8.

In Fig. 13 I have shown a detail of construction to show how the collars, such as 64^F 100 which are rigidly mounted upon the shaft 63, engage with the toothed segments, such as 64^E, which are loose on the shaft. The collar 64^F has a lug 64^F, which extends under a similar lug 64^E on the toothed segment 64^E. 105 It is evident then that when the lug 64^F is raised by the action of the weight 63^C that it will move the segment 64^E and consequently raise the core 64^B a greater or less extent, according to the position in which the collar 110 64^F is fastened onto the shaft 63. It is also evident that when the core 64^B is pulled downward by the magnet 64 it will through the connections just described move the shaft 63 to the right. After the shaft 63 has thus 115 been moved by the magnet 64 there is nothing to prevent a further movement of the shaft by some other force.

As I have described somewhat in detail the various parts of the actuator, I will now 120 describe its operation. When not in use, the various parts stand in the positions shown in the drawings. I have already shown how the magnets 60 and 61 may be used to 125 actuate the reversing-switch. If an electric cur- 130

rent is made to pass through the winding 64^A of magnet 64, the latter will become energized and will attract its core 64^B. This, as has been shown, will move the shaft 63 against the action of the weight 63^C. Thus all the other magnet-cores 65^B, 66^B, 67^B, and 68^B will be moved down as far as the core 64^B moves. At the same time through the toothed segment 63^A and gear 47^A the controller-shaft 47 will be moved a certain distance, which may be made to be equal to one step of its designed operation. Similarly the magnet 65 may be made to move the controller its second step as the shaft 63 is free to move farther in this direction, 66 may move it its third step, and so on. Evidently any required number of steps on the controller may be obtained by exciting the required number of magnets. Now when the current is shut off from the magnets 64, 65, 66, 67, and 68 they become deenergized and no longer attract their cores. The weight 63^C then will move the controller and its connected parts back to their original position.

As I have described so much of the various apparatus which I use in carrying out my invention as is necessary for a clear understanding of the operation of this invention, I will now therefore describe its application and operation. Referring to Fig. 12, and particularly to the right-hand portion of that figure, I will trace as many of the circuits there shown as will enable one skilled in the art to clearly understand the operation of all of the apparatus and of the novel system of train control which I have invented. This figure I have before stated represents a preferred wiring of two cars. The heavy line leading from the power-rail 13 designates one of the mains from the source of power-supply. The other main is grounded, as at 13'. These mains lead to a main switch 70 and thence to the controller 45 and the motor 20 in any one of the many well-known ways.

Another conductor (designated by the light line 71) leads from the positive main at the switch 70 to one terminal of the magnets 60, 61, 64, 65, 66, 67, and 68 of the actuator. When the reversing-switch 51 is in the position shown, with its handle to the left, a circuit will be established from the positive main, through the conductor 71, the magnet 60, conductor 72, magnet 34^A of the relay, conductor 73, contacts 51^B and 51^A of the reversing-switch, cut-out switch 80, which is shown in its closed position, and conductor 74 to the negative main at the switch 70. Right here I will point out that there is a cut-out switch for each master-switch on the train. Any desired cut-out switches may be closed to put their corresponding master-switches into operative relation with the various circuits. Two of them, 80 80^A, are shown closed, and two of them, 80' 80^{A'}, are shown open. All of the reversing-switches

are in their open or inoperative position except the one near the upper right-hand corner of the figure. A branch circuit will also be completed through the conductor 72', magnet 34^{A'}, conductor 73' and the other conductors and switches just pointed out. This magnet 34^{A'} and the similar magnet shown under it perform no function unless there is another car connected at that end of the car at which they are situated, so in this description I will not trace their circuits, but will only point out that their function is similar to that of the magnets 34^A, 34^B, 34^C, 34^E, 34^F, 34^G, and 34^H at the other end of the car. It is evident then from the circuits just traced that when the handle 52 of the reversing-switch 51 is in the position shown that circuits will be completed through the magnets 60 and 34^A. The magnet 60 will move the reversing-switch of the controller 45 to the desired position. The magnet 34^A of the relay 30 will attract the armature 37 of the magnetic responsive device 35^A, and will thereby close a circuit between the contacts 40 and 41. This closing between 40 and 41 will have the same effect on the second car as the closing of the reversing-switch 51 has on the first car. To be more specific, I will trace the various circuits on the second car which are closed, and thus energized, by the contacts 40 41 coming together. The conductor 41' is connected to the negative main through the cut-out switch 80^{A'} and the main switch 70^A. From the negative main then circuits are established through conductor 74^A, cut-out switch 80^A, conductor 41, contacts 41 and 40, conductor 40', magnets 34^{AX} and 34^{AY}, conductor 40', magnet 60^A of the actuator and conductor 71^A to the positive main at the main switch 70^A. It will be seen then that the reversing-switch on this second car will be moved the same as that on the first car and that two relay-magnets 34^{AX} and 34^{AY} will be energized. The first of these will have no effect, because one of the wires of its associated magnetic responsive device is a dead wire. The other relay-magnet 34^{AY} will have no effect unless there is another car connected to that end of the first car, in which case it will have the same effect upon such third car as the relay-magnet 34 has on this second car. In this way any desired number of cars may be added to the train, and they may all be controlled from any selected master-switch. It will also be seen that the amount of current which passes through the master-switch which is used does not increase when the number of cars in the train is increased. Consequently there need be little or no sparking at the contacts of the reversing-switch.

I have thus described quite fully the operation of my improved system and apparatus when one of the reversing-switches is moved

to the left. When the latter is moved to the right, the magnets 61 and 61^A will be energized and the actuator will cause the controllers 45 to reverse the connections to the motors 20 20 in a well-known way. At the same time the relay-magnet 34^B and the corresponding relay-magnets on the train will be energized.

In a similar manner when the controlling-switch 53 is moved to the left until its contacts bridge contacts 53^A and 53^C a circuit will be closed through the actuator-magnet 64 and it will be energized and cause the controller to be moved one step. This will have the desired effect upon the motor 20 on that car. At the same time through relay-magnet 34^C and the other relay connections similar to those already described in detail the magnets on the other actuators on the train which correspond to magnet 64 on the first car will be energized and will have a similar effect.

When the controlling-switch arm is moved around onto contacts 53^D, 53^E, 53^F, and 53^G, the actuator-magnets 65, 66, 67, and 68 will be energized, respectively, and the motor-controller moved correspondingly, and through the relay-magnets 34^D, 34^E, 34^F, and 34^G and their connections a similar operation will occur at the same time on the other cars.

This system may be applied to a train made up partly of motor-cars and partly of idle cars or trailers, as shown in Fig. 2, and any person skilled in the art will be able to make the necessary changes to thus apply it.

I have shown that each motor-car is complete in itself. All wire connections between the cars are dispensed with. The cars may therefore be readily connected together without the handling of live wires or the liability of disastrous effects due to wrong connections. It will also be noticed that no current is transmitted from car to car and that the current in the master-switch, which is used to control the train, will remain the same regardless of the number of cars in the train.

I have shown but one motor on each motor-car; but it is evident that two or more motors may be placed on these cars. The main motor-circuits may be connected between the cars, if desired. Many other modifications and alterations of this invention may be made without departing from its spirit.

I do not wish to confine myself to the exact apparatus or electrical connections which I have herein shown and described, as they are shown merely to illustrate my invention, which is obviously capable of many changes and modifications.

What I claim is—

1. In combination with two cars, electrical circuits on the cars, and a relay associating the circuits on the two cars.

2. In combination with two cars, a plurality of electrical circuits on each of the cars, and a plurality of electromagnetic devices associating the circuits. 65

3. In combination with two cars, electrical circuits on the cars, a relay associating the circuits, and means for flexibly connecting the relay to the cars. 70

4. In combination with two connected cars adapted to carry goods or passengers, a two-part relay between the cars. 75

5. In combination with two cars, a two-part relay between the cars, one part of which is supported by one of the cars and the other part of which is supported by the other of the cars. 80

6. In combination with two cars, a two-part relay between the cars, one part of which is flexibly supported by one of the cars and the other part of which is flexibly supported by the other of the cars. 85

7. In combination with two cars, a two-part relay, one part of which is on one of the cars and the other part of which is on the other car, and means for uniting the two parts. 90

8. In combination with two cars, a two-part relay, one part of which is on one of the cars and the other part of which is on the other car, and means for yieldingly uniting the two parts. 95

9. The combination with a plurality of connected cars adapted to carry goods or passengers, electrical circuits on the cars, and relays between the cars adapted to operatively associate the circuits. 100

10. In combination with a plurality of cars electrical circuits on the cars, relays between the cars adapted to operatively associate the electrical circuits and a switch arranged to control said circuits. 105

11. In combination with a plurality of cars, electrical circuits on the cars, relays between the cars adapted to operatively associate the electrical circuits, and switches on each car for controlling the electrical circuits. 110

12. In combination with a plurality of cars, electrical circuits on the cars, relays between the cars adapted to operatively associate the electrical circuits, and switches on each car any one of which may be used for controlling the electrical circuits. 115

13. In combination with a plurality of connected cars, electrical circuits on the cars, and relays between the cars adapted to operatively associate the electrical circuits and arranged to render such circuits inoperative should the cars become separated. 120

14. The combination with a plurality of cars of a motor and a controlling-circuit therefor on each car and relays for operatively associating the controlling-circuits. 125

15. The combination with a plurality of cars of a motor and a controlling-circuit

- therefor on some of the cars, and relays for operatively associating the controlling-circuits.
16. The combination with a plurality of 5 cars, of motors and controlling-circuits therefor, relays for operatively associating the circuits between the cars and a switch in the controlling-circuit.
17. The combination with a plurality of 10 cars, of a motor and a controlling-circuit therefor on each car, relays for operatively associating the controlling-circuits and a switch on each car in the controlling-circuit.
18. The combination with a plurality of 15 cars, of a motor and a controlling-circuit therefor on each car, relays for operatively associating the controlling-circuits, and means for controlling the motors from any selected car.
19. The combination with a plurality of 20 cars, of a motor and a controlling-circuit therefor on each car, relays for operatively associating the controlling-circuits, and means for controlling the motor from any selected car whereby the motor may be started in either direction.
20. The combination with a plurality of 25 cars, of motors and controlling-circuits on the cars, relays for associating the controlling-circuits between the cars, master-switches at both ends of each car, and means for operatively connecting the master-switches with the controlling-circuits.
21. The combination with a plurality of 30 cars, of motors and controlling-circuits on the cars, relays for associating the circuits between the cars, master-switches on the cars connected in the controlling-circuits, and means for rendering any desired master 35 switch or switches inoperative.
22. The combination with a plurality of cars of a motor and a controlling-circuit therefor on each car, and relays for associating the circuits so that they will be mutually 40 operative when the cars are together.
23. The combination with a plurality of cars, of a motor and a controlling-circuit therefor on each car, and a relay on the end of each car for associating the circuits so that 45 they will be mutually operative only when the cars are together.
24. In an electric train, the combination of two or more motor-cars, one or more cars without motors, controlling-circuits for the 50 motors, and relays between all of the cars for operatively associating the controlling-circuits.
25. In an electric train, the combination of two or more motor-cars, one or more cars 55 without motors, controlling-circuits for the motors and relays between all of the cars for operatively associating the controlling-circuits, and means for controlling the motors from a selected platform of any of the motor-cars.
26. In combination with two cars, electrical circuits on the cars, and a relay connecting the circuits on the two cars, said relay being inclosed by a water-tight housing. 60
27. In combination with two cars, a two-part relay between the cars, each part being inclosed in a water-tight housing.
28. In combination with two cars, a plurality of electrical circuits on the cars, and a relay, comprising a plurality of electromagnets, controlling the circuits on the two cars. 70
29. In combination with two cars, a plurality of electrical circuits on the cars, and a two-part relay between the cars, each part comprising a plurality of electromagnets and 75 a plurality of magnetic responsive devices.
30. In combination with two cars, a plurality of electrical circuits on the cars, and a two-part relay between the cars, each part comprising a plurality of electromagnets and 80 a plurality of magnetic responsive devices arranged to control the circuits on the two cars.
31. In combination with two cars, a plurality of electrical circuits on the cars, a two-part relay between the cars, each part comprising a plurality of electromagnets and a plurality of magnetic responsive devices and inclosed in a water-tight housing, said relay being arranged to control the circuits on the 85 two cars.
32. A plurality of cars, controlling-circuits on the cars, and electromagnetic relays between the cars arranged to cause the controlling-circuits on the several cars to act together. 90
33. A plurality of cars, independent controlling-circuits on the cars, master-switches for said circuits, and electromagnetic relays between the cars arranged to cause the controlling-circuits to act together. 95
34. A plurality of cars, independent controlling-circuits on the cars, master-switches for said circuits, and electromagnetic devices between the cars arranged to cause the controlling-circuits to be controlled together from any one of the master-switches. 100
35. A plurality of cars, independent controlling-circuits on the cars, master-switches on the platforms of the cars and relays between the cars arranged to be actuated by any selected master-switch and by each other 105 to control the controlling-circuits.
36. The combination of two cars, a master-switch on each car, a relay between the cars, said switches and said relay each comprising a plurality of circuit-closers, and a plurality of independent controlling-circuits on each car connected to the master-switch on the car on which said circuits are situated and to 110 the relay.
37. The combination of two cars, a master-switch on each car, a two-part relay between the cars, one part of which is on one of the cars, and the other part of which is on the 115 cars. 120

other of the cars, said master-switches and each part of said relay comprising a plurality of circuit-closers, and a plurality of independent circuits on each car connected to the master-switch and to the part of the relay which is on the car on which said circuits are situated.

38. A plurality of cars, independent controlling-circuits on the cars, master-switches for said circuits, means for rendering each of said master-switches operative or inoperative, and electromagnetic devices between the cars arranged to cause the controlling-circuits to act together.

15 39. A plurality of cars, independent controlling-circuits on the cars, master-switches for said circuits, means for rendering each of said master-switches operative or inoperative, and electromagnetic devices between the cars arranged to cause the controlling-circuits to be controlled together from any of the master-switches.

40. A plurality of cars, a direct-current-control system for said cars and wireless communication between the cars for the control system.

41. The combination with a plurality of cars, of motors, controllers therefor, suitable electrical circuits, and relays for operatively associating the circuits on the several cars.

42. The combination with a plurality of cars of electric motors, controllers therefor, suitable electrical circuits, master-switches, and relays for operatively associating the circuits on the several cars.

43. The combination with a plurality of cars of electric motors, controllers therefor, suitable electrical circuits, master-switches, means for connecting or disconnecting the master-switches with or from the circuits, and relays for operatively associating the circuits on the several cars.

44. The combination with a plurality of cars, each car having a motor, a controller therefor, suitable electrical circuits, and a master-switch, and relays between the cars for operatively associating the electrical circuits.

45. The combination with a plurality of cars each of which has a motor, a controller therefor, a master-switch and suitable electrical connections, and means comprising a relay between the cars for operatively associating the several circuits so that all the motors may be operated from any selected master-switch.

46. The combination with a plurality of cars each of which has a motor, a controller therefor, a master-switch and suitable electrical connections, and means comprising a relay between the cars for operatively associating the circuits so that the controllers may be actuated to start, stop or control the speed of all the motors from a master-switch on any selected car.

47. The combination with a plurality of cars, of electric motors, controllers therefor, electromagnetic actuators for the controllers, suitable electrical circuits, and relays for operatively associating the circuits on the several cars.

48. The combination with a plurality of cars, of electric motors, controllers therefor, electromagnetic actuators for the controllers, suitable electrical circuits, master-switches, and relays for operatively associating the circuits on the several cars.

49. The combination with a plurality of cars, of electric motors, controllers therefor, electromagnetic actuators for the controllers, suitable electrical circuits, master-switches, means for connecting or disconnecting the master-switches with or from the circuits, and relays for operatively associating the circuits on the several cars.

50. The combination with a plurality of cars, each car having a motor, a controller therefor, an electromagnetic actuator for the controller, suitable electrical circuits and a master-switch, and relays between the cars for operatively associating the electrical circuits.

51. The combination with a plurality of cars each of which has a motor, a controller therefor, an electromagnetic actuator for the controller, a master-switch and suitable electrical connections, and means comprising a relay between the cars for operatively associating the several circuits so that all the motors may be operated from any selected master-switch.

52. The combination with a plurality of cars, each of which has a motor, a controller therefor, an electromagnetic actuator for the controller, a master-switch and suitable electrical connections, and means comprising a relay between the cars for operatively associating the circuits so that the controllers may be actuated to start, stop or control the speed of all the motors from the master-switch on any selected car.

53. The combination with a plurality of cars, each car having a plurality of motors, a controller for the motors, an electromagnetic actuator for the controller, suitable electrical circuits, and relays between the cars for operatively associating the electrical circuits.

54. The combination with a plurality of cars, each car having a plurality of motors, a controller for the motors, suitable electrical circuits, one or more master-switches, means for connecting or disconnecting the master-switches with or from the circuits, and relays between the cars for operatively associating the electrical circuits.

55. The combination with a plurality of cars, of electric motors, electrical circuits therefor, means for reversing the motors, and relays for operatively associating the circuits on the several cars.

56. The combination with a plurality of cars, of electric motors, electrical circuits therefor, electromagnetic means for reversing the motors, and relays for operatively associating the circuits on the several cars.

57. The combination with a plurality of cars, of electric motors, magnetically-actuated reversing - switches therefor, suitable electrical circuits, a manually-operated switch for controlling the circuits, and relays between the magnetically-operated reversing-switches arranged to cause them to act simultaneously.

58. The combination with a plurality of cars, of electric motors, controllers therefor, electromagnetic actuators for the controllers, a master-switch, an independent reversing-switch and magnets for reversing the motors, suitable electrical circuits, and relays for operatively associating the circuits on the several cars.

59. The combination with a plurality of cars, of electric motors, controllers therefor, electromagnetic actuators for the controllers, a master-switch, an independent reversing-switch and magnets for reversing the motors, means for locking the reversing-switch except when the controllers are in their off position, suitable electrical circuits, and relays for operatively associating the circuits on the several cars.

60. In a train-control system, motors and controllers on some of the cars, magnetic actuators for the controllers, a master-switch or master-switches on one or more of the cars, electrical circuits and relays between the cars

arranged to cause the actuators to be moved together.

61. In a train-control system, motors and controllers on some of the cars, magnetic actuators for the controllers, a master-switch or master-switches on one or more of the cars, means in said switches for automatically controlling the movement of the actuators, electrical circuits and relays carried by the cars arranged to cause the actuators to be moved together.

62. In a train-control system, motors and controllers on some of the cars, magnetic actuators for the controllers, a master-switch or master-switches on one or more of the cars, means in said switches for automatically controlling the movement of the actuators, electrical circuits, and relays carried by the cars for associating the circuits and causing the actuators to move together.

63. In a train-control system, a plurality of motors and controllers, electromagnetic actuators for the controllers, electrical circuits, master-switches for controlling the actuators step by step, means in the actuators for returning the controllers to off position step by step, and relays for positively associating the circuits on the several cars.

In witness whereof I have hereunto signed my name in the presence of two subscribing witnesses.

AUGUST SUNDH.

Witnesses:

ERNEST W. MARSHALL,
LEWIS J. SMITH.
